US00D806713S

(12) **United States Design Patent** (10) Patent No.: **US D806,713 S**
(45) Date of Patent: ** Jan. 2, 2018

(54) **TABLET CASE**

- (71) Applicant: **CATALYST LIFESTYLE LIMITED**,
North Point (HK)
- (72) Inventors: **Joshua Wright**, Hong Kong (CN);
June Lai, Hong Kong (CN)
- (73) Assignee: **CATALYST LIFESTYLE LIMITED**,
North Point, Hong Kong (CN)

(**) Term: **15 Years**

(21) Appl. No.: **29/609,966**

(22) Filed: **Jul. 7, 2017**

(51) LOC (11) Cl. **14-02**
(52) U.S. Cl.
USPC **D14/440**

(58) **Field of Classification Search**

USPC D14/440, 250, 447, 433, 434; 206/45.23,
206/320, 45.2; 361/679.55; 294/25;

(57) **CLAIM**

The ornamental design for a tablet case, as shown and described.

DESCRIPTION

FIG. 1 is a perspective view including a rear, bottom and one side of the tablet case;

FIG. 2 is a perspective view including a rear, top and an opposite side of the tablet case;

FIG. 3 is a perspective view including a front, bottom and a side of the tablet case;

FIG. 4 is a perspective view including a front, top and an opposite side of the tablet case;

FIG. 5 is a planar view of the rear of the tablet case of FIG. 1;

FIG. 6 is a planar view of the front of the tablet case of FIG. 1;

FIG. 7 is a planar view of the side of the tablet case of FIG. 1;

FIG. 8 is a planar view of the opposite side of the tablet case of FIG. 1;

FIG. 9 is a planar view of the top of the tablet case of FIG. 1; and,

FIG. 10 is a planar view of the bottom of the tablet case of FIG. 1.
